[57] **CLAIM**

The ornamental design for a combined cover and dispenser for a jar or the like, substantially as shown.

DESCRIPTION

FIG. 1 is a top perspective view of a combined cover and dispenser for a jar or the like, showing my new design.

FIG. 2 is a top plan view.

FIG. 3 is a side elevation view, the opposite side being the mirror image thereof.

FIG. 4 is a bottom plan view.

FIG. 5 is a front elevation view.

FIG. 6 is a rear elevation view.

FIG. 1

FIG. 2

FIG. 5

FIG. 3

FIG. 4

FIG. 6
